United States Patent Office

Des. 220,556
Patented Apr. 20, 1971

220,556

TOOL BOX, OR SIMILAR ARTICLE

Jack Evans, Grant Park, Ill. 60940

Filed Feb. 4, 1969, Ser. No. 15,616

Term of patent 14 years

Int. Cl. D3—99

U.S. Cl. D87—1

FIG. 1 is a perspective view of a tool box, or similar article, showing my new design;

FIG. 2 is a front side elevation view thereof;

FIG. 3 is an end elevational view thereof;

FIG. 4 is a top plan view thereof;

FIG. 5 is a rear side elevational view thereof;

FIG. 6 is a bottom view thereof; and

FIG. 7 is a perspective view of the tool box, or similar article, with the top open.

I claim:

The ornamental design for a tool box, or similar article, as shown.
